UNITED STATES PATENT OFFICE.

BENJAMIN F. WOODING, OF MONTCLAIR, NEW JERSEY, ASSIGNOR TO WOODING RAILWAY WARNING DEVICE COMPANY, OF DENVER, COLORADO, A CORPORATION OF ARIZONA.

RAILWAY-TRAFFIC-CONTROL APPARATUS.

1,216,038.

Specification of Letters Patent. Patented Feb. 13, 1917.

Application filed November 24, 1915. Serial No. 63,146.

To all whom it may concern:

Be it known that I, BENJAMIN F. WOODING, a citizen of the United States, and a resident of Montclair, in the county of Essex and State of New Jersey, have invented a new and Improved Railway-Traffic-Control Apparatus, of which the following is a full, clear, and exact description.

Among the principal objects which the present invention has in view are: to provide means for controlling railway traffic in accordance with roadbed characteristics; to provide members of the rolling stock of a railway equipment with apparatuses operable from the roadbed to be normally operated when said members are traveling at predetermined speeds and abnormally operated when the members are moving at other than said predetermined speeds; to provide means manually operated for releasing the control of the track equipment; and to provide a track equipment which may be varied in its effect upon the apparatuses carried by the moving members to multiply the variety of effects in the operation thereof.

Drawings.

Figure 1 is an assemblage of the parts of the apparatus carried by members of the rolling stock, and showing a fragment of roadbed equipment for operating in conjunction therewith, said parts being diagrammatically disposed;

Fig. 2 is a cross section of switch terminal and switch members co-operating therewith, the section being taken as on the line 2—2 in Fig. 1;

Fig. 3 is a side elevation of an axle journal box for a railway vehicle and switch boxes mounted thereon, the switch boxes being shown in section, the section being taken as on the line 3—3 in Fig. 4;

Fig. 4 is a vertical section taken as on the line 4—4 in Fig. 3;

Fig. 5 is a detail view in section, showing the contact member for operating the controlling apparatus of the moving members;

Fig. 6 is a section taken as on the same line as Fig. 4, showing the normal service disposition of the parts of the contact apparatus;

Fig. 7 is a similar view showing the parts of the contact apparatus as abnormally disposed;

Figs. 8, 9 and 10 are diagrammatic views showing the trackbed equipment.

Description.

As seen in the drawings, the apparatuses carried by the moving members, each employs a U-shaped blade 15, which blade is rigidly connected with terminal blocks 16, pivotally mounted by bolts 17 in contact boxes 18 permanently and rigidly mounted on axle journal boxes 19 at opposite sides of the moving members so equipped.

Both of the boxes 18 are insulated by a pad 20, from the journal boxes 19, and each is provided with outlets extending through the upper side thereof for insulated wires 21 and 22, which form a local circuit incorporating a battery 23 and a magnet 24 carried by each of said moving members. The box 18 having the wire 21 is permanently in circuit therewith and with the block 16 contained in said box. In the opposite box 18, however, the wire 22 is connected by a binding post 25 with a spring blade contact terminal 26. The blocks 16 have each an extension 27, which is normally pressed against the terminal 26, by a spring 28, which, as seen best in Fig. 4 of the drawings, normally disposes the blocks 16 and blades 15 connected therewith in a position inclined to the face of the box 18. This is the position assumed by the blades 15 and members connected therewith when not controlled by the roadbed characteristics above referred to. These characteristics are ramps arranged to engage and swing the blades 15 from the position shown in Fig. 4 of the drawings to the position shown in Fig. 6 of the drawings.

When the blades 15 and blocks 16 are held by the springs 28 in the position shown in Fig. 4 of the drawings, the local circuit embodying the battery 23 and magnet 24, is closed, and the magnet 24 being energized draws the armature cap 29 toward the said magnet and holds the ball valve 30 seated over the outlet of the air-bleeding pipe 31, which is connected with the train pipe of the air-brake system with which the moving member is equipped.

Incorporated in the local circuit, is a direction-indicating switch having a movable switch blade 32 and separated terminal plates 33. The blade 32 is mounted on a pivot shaft 35, which supports a lever 36,

having a hand grip 37. The blade 32 is preferably furnished with a round wiping member, which makes contact with the plates 33 and 34 and conforms to the upturned juxtaposed edges 39 thereof, which facilitates the passage or jump of the blade from one operative position to the other, the said switch being used for disposing the apparatus in operative condition to conform with the forward or rearward movement of the moving member.

As shown best in Fig. 1 of the drawings, the blade 32 has a spring section *a*, which normally presses the member 38 against the plates 33, 34, and permits the outward movement of said member when passing over the outturned edges 39 with which the said plates are provided. The blade 32 is also provided with a spring section *b* disposed in a plane perpendicular to the plane of the section *a*, which permits the member 38 to be pressed backward when the lever 36 is thrown from one working position to the other, and when the said member passes over the edges 39. In this way, the member 38 is permitted to carry the contact across the gap between the two plates 33 and 34, but prevented from resting at the apex or ridge thereof. In other words, by means of this arrangement, the correct working position of the member 38 with reference to the plates 33 and 34, is assured, thereby providing for the operation of one only of the blades 15, and at one side of the moving member carrying the same.

It will be observed that the valve 30 is normally maintained in closed relation to the pipe 31, and that the armature cap 29 holds the same in this position when drawn to the magnet 24. It will also be observed that if the magnet 24 is deenergized, the valve 30 and armature cap 29 will be lifted by the air in the pipe 31 away from the opening of said pipe, and that thereafter because of the extended area of the armature cap 29, the air pressure will resist the pull of the magnet 24, to prevent the seating of the valve 30 until the air pressure in the pipe 31 is less than the pull of the magnet. Therefore, it will be seen that if the local circuit be broken, it cannot be reestablished until after the train-pipe pressure has been reduced to a point where the brakes are applied and the moving member has been brought to rest.

As seen best in Figs. 3, 4 and 6 of the drawings, the blade 15, blocks 16, and the extension 27 thereof, complete the circuit, energizing the magnet 24, employing the wires 21, 22 and the terminals 26 and 43. In the position shown in Fig. 4, it will be observed the blade 15 is inclined from the vertical. As seen in Fig. 6 of the drawings, when the blade 15 is moved to the vertical, the extension 27 is disengaged from the

terminal 26 and is engaged with the swinging block 42. The swinging block 42 is moved by the extension 27 when assuming the position mentioned, to engage the contact terminal 43 with which the wire 40 is electrically connected, using for this purpose a binding post 44.

The magnet 24 is energized by three distinct circuits, any one of which being completed serves to maintain the valve 30 closed. These circuits may be designated as the "normal", the "signal", and the "permission", circuits. When traced on the drawings, the "normal" circuit will be found to incorporate the battery 23, wire 22, terminal 26, blade 15, wire 21, blade 32, magnet 24, ground connection 46^a, and ground connection 23^a. This circuit is maintained by the spring 28, when the moving member is between signal stations. The "signal" circuit incorporates the supply or battery 46, rail 45, blade 15, wire 21, blade 32, magnet 24, and ground connection 46^a. This circuit is maintained while the moving member is passing the signal station, and is completed prior to the discontinuance of the "normal" circuit by removing the extension 27 from contact with the terminal 26. The "permission" circuit incorporates the battery 23, switch 41, wire 40, terminal 43, block 42, blade 15, wire 21, blade 32, magnet 24, ground connection 46^a, and ground connection 23^a.

The "normal" circuit may be said to be independent of track conditions. The "signal" circuit is dependent on the condition of the track ahead, the supply or battery 46, which is located at the far end of the forward block of the track, being short-circuited by a moving member or other obstacle between said supply and the signal station past which the member is moving. The "permission" circuit is independent of track conditions, but is dependent on the driver of the moving member.

The opening of all the circuits enumerated at any one time, deenergizes the magnet 24 and permits the air pressure in pipe 31 to lift and maintain lifted, the valve 30 and cap 29. This happens whenever the blade 15 is engaged by a rail 45 of a signal station, which at the moment is not supplied with current by the source or battery 46, and when the driver has not closed the switch 41, or, in other words, when through any inattention on the part of the driver, the visual signal with which the roadbed is conventionally supplied, is unheeded by him, when the same is set to indicate caution or danger.

The "permission" circuit is provided to enable the driver to move past a signal station set to indicate either caution or danger, and to this end, introduces the circuit so named, which incorporates the switch 41,

which is manually operable and manually retained. The employment in this connection of the "permission" circuit enables the driver to move his engine or train past the signal station into the danger zone, but in so doing, he is fully alert to the condition of said zone. This permits the congestion of the traffic conditions often necessary to the proper operation of a railway system. It also provides for the need of making up time in the operation of the moving member, and it further permits a following moving member to move into the danger zone to the assistance of a moving member held by damage in the block ahead.

In every instance, however, the operation of the apparatus insures that the engineer who passes a signal station indicating danger conditions, is apprised of the fact that he has entered a danger zone. To this end, he is compelled to establish the "permission" circuit prior to reaching the signal station, and also is compelled to manually maintain closed the switch 41 until he has passed said station, when the spring 28 would re-establish the "normal" circuit.

A further advantage in the employment of the "permission" circuit, is that it allows a driver to move his vehicle past signal stations having permanent characteristic signal conditions, as, for instance, where a caution signal is permanently set, to provide for reduction in speed incident to the presence of a dangerous curve, down-grade, draw bridge, or other danger characteristics in the block ahead. These conditions might not necessarily require reduction of speed with the consequent loss of time, if the alertness of the driver could be assured.

The operation of the present invention insures this alertness on the part of the driver.

As shown in Figs. 8, 9 and 10, the roadbed of a railway system when employing apparatuses constructed as above described, is equipped with ramps each employing a contact rail 45. The rail 45, when arranged as shown in the figures of the drawing referred to and as further disclosed in Fig. 1 of the drawings, serves a double purpose, to wit, that of furnishing current to the magnet 24 supplied from an independent or track source indicated by the battery 46, and to provide safety means operable adjunctively to the traffic controls of the signal system employed.

It will be observed by reference to Figs. 8 to 10, inclusive, that the rails 45 forming the ramps, have inclined portions indicated in said figures by the letters A, B and C, respectively.

The employment of the portions A, B and C of the ramps and rails 45 thereof, is adjunctive to the signal system, and corresponds thereto by varying the length of the said portions. It will be understood that the

deflection of the blade 15 from the position shown in Fig. 4 of the drawings to that shown in Fig. 6 of the drawings, is constant, that is, over the same distance whether the inclined portion be short, as shown by the letter "A" in Fig. 8, or long, as shown by the letter "C" in Fig. 10. It will be seen, however, that for a predetermined rate of speed, the rapidity of the deflection of the blade when passing over the portion A is materially different from that when the blade is passing over the portion C. This feature is utilized in the present invention to provide in the track equipment where the cautionary signals are permanent, means for indicating track characteristics and for controlling the speed on entering the block with which the ramps are associated.

The portions A, B and C are lengthened or shortened in correspondence with what may be termed the normal rates of speed adopted for traffic on the roadbed. For the sake of illustration, it is assumed that when the moving member is traveling at the maximum rate of speed, the portion shown in Fig. 10 and indicated by the letter "C" is inclined, so that the blade 15 and parts connected therewith are deflected at a normal rate of speed, from the positions shown in Fig. 4 of the drawings, to the positions shown in Fig. 6 of the drawings. This would correspond to an angle in the rail 45, which would move the blade 15, the block 16, the extension 27, and block 42, from the positions shown in Fig. 4 of the drawings, to the positions shown in Fig. 6 of the drawings, where the block 42 would remain balanced on its pivot 47 in contact with the terminal 43.

If in equipping the roadbed, it is necessary to place a fixed caution, indicating reduced rate of speed, the rail 45 is so shaped that the inclined portion will correspond with the portion B or the portion A in Figs. 9 and 8, to indicate reduction to a greater or less extent. If the rail 45 is shaped to provide the inclined portion B, it will be observed that the length of said portion being about half the length of the portion C, would require that the speed of the moving member be reduced to about one-half of that permitted by the portion C in order that the same rapidity of deflection of the blade 15 and parts associated therewith be maintained. If it were designed to further reduce the rate of speed permitted by the moving member the rail 45 would be shaped to have the portion A shown in Fig. 8 of the drawings. The portion A being about one-half of the length of the portion B, a further diminution in the rate of speed of the moving member to obtain the same rate of deflection of the blade 15 and parts associated therewith, would be required. From this it

will be seen that providing ramps having rails 45 with inclined portions at the terminals thereof, the rates of speed permitted by the moving members may be varied indefinitely.

When the blades 15 and parts associated therewith are moved at a rate of speed greater than that designed, the block 42 is thrown past the contact with the terminal 43, to assume the position shown in Fig. 7 of the drawings. Any suitable means may be employed for rendering the block 42 more sensitive to the speed at which it is rotated. That shown in the present disclosure is a weight 48 removably mounted in the block 42. By varying the weight 48, the action of the block may be rendered more sensitively responsive to the inertia produced by the deflection of the blade 15 and extension 27.

It will be understood that at signal stations set to caution or danger signals, the rail 45 is uncharged with current. Therefore, in order to pass the station, the driver 25 is compelled to operate the switch 41 and establish the "permission" circuit in which is incorporated the terminal 43, into engagement with which the block 42 is moved when the blade 15 is thrown to the vertical position. If the driver wilfully or carelessly undertakes to pass the signal station without reducing speed, the sharper inclination of the portion B or A, as the case may be, with which the rail 45 at the station is provided, will deflect the blade 15 to move the block 42 at a higher rate of speed, which will carry the block past engagement with the terminal 43, breaking the "permission" circuit. The "normal" circuit being open 40 by the removal of the extension 27 from the terminal 26, and the "signal" circuit being open due to the lack of current in the rail 45, all the circuits are open when the block 42 thus passes out of contact with the terminal 43. The magnet 24 is thus deenergized and the valve 30 and cap 29 are lifted by the pressure in the pipe 31, with the result that the brakes on the moving member will be set.

50 It will be understood that while the normal rate of speed of travel on the trackbed is provided for, the moving members may operate at rates of speed far in excess of or less than those designed, without reference 55 to the movement of the block 42. If the rail 45 is charged, the "signal" circuit is closed and the magnet 24 remains active. The operation of the inclined portions A, B and C of rails 45, will thus be understood to have 60 relation only to the fixed stations, which correspond with track or roadbed characteristics.

While the apparatus herein described may be operated by any track equipment employing deflector current-supplying ramps, it is

particularly adapted for use in conjunction with ramps constructed and arranged in accordance with the invention set forth in the companion application, filed November 9, 1915, and bearing Serial No. 60,605. For more detailed description of the construction and the employment of these ramps, cross reference is here made to said application.

Claims:

1. An apparatus as characterized comprising electroactive closure means for normally restraining an expansive fluid supply, said means embodying an electric supply; a closed normal circuit therefor; an exposed switch member extending to near the roadbed and operable therefrom for opening said normal circuit; a permission circuit embodying said electric supply and said closure means, said circuit being closed by said switch member in correspondence with the opening of said normal circuit whereby said closure means is optionally maintained active by relatively independent circuits successively actuating said means; a plurality of devices permanently mounted on the roadbed for moving said switch member, all of said devices adapted to move said switch member equally, said devices being individually characterized by different lineal switch-moving portions; and a fugitive connection incorporated in said permission circuit and operable by said switch member for completing said permission circuit, said fugitive connection being adapted to break the connection if moved in excess of a designed rate of speed.

2. An apparatus as characterized comprising electroactive closure means for normally restraining an expansive fluid supply, said means embodying a closed normal circuit; an exposed switch member extending to near the roadbed and operable therefrom for opening said normal circuit; a normally inactive signal circuit embodying an independent electric source and said closure means, said signal circuit being closed by said switch member in correspondence with the opening of said normal circuit, whereby said closure means is maintained active by relatively independent circuits successively; a plurality of devices permanently mounted on the roadbed for moving said switch member, each of said devices adapted to move said switch member equally, and individually characterized by varying lineally the switch-moving portion thereof; a permission circuit embodying said closure means and the electric supply thereof; a fugitive connection incorporated in said permission circuit and operable by said switch member for completing said permission circuit, said fugitive connection being adapted to open said permission circuit if moved in excess of a predetermined rate.

of speed; and means for varying the inertia of said fugitive member.

3. In combination, an electrically actuated air-brake control apparatus embodying an exposed rocking switch for normally closing the operating circuit of said apparatus; and a plurality of roadbed devices adapted for rocking said switch when the same is moving past said devices, said devices being individually differentiated to rock said switch at different rates of speed when said switch is traveling at a constant rate of speed.

4. An apparatus as characterized comprising an electro-mechanically operated valve for closing the outlet of the train pipe of a pneumatic brake system of a moving member; a switch carried by said member and extended in juxtaposed relation to the roadbed over which said member travels; a plurality of track devices fixedly disposed on said roadbed over which said moving member travels for operating said switch; a plurality of operating circuits each embodying said valve and said switch; a plurality of electric supply sources, each connected with one of said circuits, one of said sources being carried by the moving member and the other electrically connected with said track; and manually controlled means for completing the circuit embodying the electric supply carried by said moving member during the period when the normal circuit embodying the same is opened by said switch.

5. An apparatus as characterized comprising an electro-actuated closure valve, an

electric supply, and a switch extended in juxtaposed relation to the roadbed over which the apparatus is moved for operation by track devices thereon; a plurality of circuits incorporating said supply, said valve, and switch; a fugitive contact incorporated in one of said circuits, said contact being operatively connected with for movement by said switch, said contact being adapted for engaging a terminal for completing the circuit in which it is incorporated and to pass beyond and out of contact with said terminal when too rapidly moved.

6. An apparatus as characterized comprising an electro-actuated closure valve, an electric supply, and a switch extended in juxtaposed relation to the roadbed over which the apparatus is moved for operation by track devices thereon; a plurality of circuits incorporating said supply, said valve, and switch; a fugitive contact incorporated in one of said circuits, said contact being operatively connected with for movement by said switch, said contact being adapted for engaging a terminal for completing the circuit in which it is incorporated and to pass beyond and out of contact with said terminal when too rapidly moved and manually controlled means for completing the circuit in which said fugitive contact is contained.
